UNITED STATES PATENT OFFICE.

ALBERT KAUFMANN, OF BERLIN, GERMANY.

DIE-CASTING MACHINE.

Application filed April 16, 1924. Serial No. 707,000.

To all whom it may concern:

Be it known that I, ALBERT KAUFMANN, a citizen of Germany, and residing at 99 Kaiserdamm, Berlin, Germany, have invented certain new and useful Improvements in Die-Casting Machines, of which the following is a specification.

This invention relates to die-casting machines and particularly to machines of this kind in which the mold is moved by hand to the outlet through which the metal is ejected from the crucible. In accordance with one feature of the invention the mold, when moved towards the metal outlet, strikes against an arm or lever that causes the drive of the pump that ejects the metal to be automatically put into operation.

The drive of the metal ejecting pump is then automatically thrown off after the driving shaft has turned through a certain angle or has executed a complete revolution.

Another feature of the invention consists in providing a coupling between the mechanism that sets the drive in operation and the members that control the said mechanism. This coupling has to be kept in its operative position by the operator who attends to the machine in order to enable the motion of the controlling member to be transmitted to the coupling mechanism. By this means the operation of the metal ejecting pump while the mold is being set in its proper position is obviated, and the operation of the metal ejecting pump is thus also prevented in cases in which unauthorized persons move the mold towards the metal outlet without understanding the operation of the machine.

A die-casting machine in accordance with the invention also offers the considerable advantage that the working stroke of the pressure piston is not effected as in known machines by spring power but positively by a cam mounted on the driving shaft, while the return stroke of the piston may be effected by a helical spring or a second cam. To enable castings of various sizes to be made with one and the same cam the rods which drive the pressure piston are provided with spring joints, the springs of which are compressed so as to permit the rods to expand when the mold is filled with metal and to thus enable the cam to continue its rotation without damaging the said rods.

The die-casting machine according to the

invention is easy to operate and is capable of working at a high speed. The machine cannot be damaged by mistakes on the part of the operator and, while acting with certainty, its construction is comparatively simple.

The invention is shown by way of example in the drawing in which—

Fig. 1 is a side view of the jet casting machine,

Fig. 2 is a plan view,

Fig. 3 a section on the line III—III of Fig. 1.

Figs. 4—7 show details, Fig. 4 being a section on the line IV—IV of Fig. 2, Fig. 5 a section on the line V—V of Fig. 2 and Fig. 6 a longitudinal section through the coupling member between the driving shaft and driving pulley, Fig. 6^a being a partial transverse section on the line VI—VI. Fig. 7 shows a part of the driving rods of the pressure piston on an enlarged scale and Fig. 8 a section corresponding to Fig. 3 of a modified die-casting machine.

The die-casting machine consists of a frame *a*, a crucible *b* with a furnace, a pressure cylinder *c* with a pressure piston *d* and a mold *e*, which latter is adapted to be moved in a horizontal direction on the frame *a* up to the metal outlet *f* at the side of the crucible. The mold is reciprocated in the machine illustrated by a rack and pinion drive adapted to be operated by a handle *g*.

The reciprocation of the mold may, however, also be effected by other means. Mounted in journals on the frame *a* of the machine is a set of levers or links *h*, *i*, *k* adapted to be turned on a pivot *l* as shown in Fig. 1.

The lever *h* is situated in the path of the mold *e* so that it is operated when the latter is moved to the metal outlet *f*. When the lever *h* is thus moved a short shaft *m* journaled in a bearing on the frame *a* is turned.

Attached to the end of the shaft *m* is one half *n* of a clutch, the other half *o* of which is attached to the end of a shaft *p* which is mounted to be moved axially in bearings *a'* attached to the frame of the machine. A spring *q* arranged at one end of the shaft *p*

tends to turn the shaft *p* into its normal rotary position and also to push it towards the left. The shaft *p* is shifted longitudinally in the direction of the arrow *r* by means of a crank *s* and a pedal *t*. This shifting motion is for the purpose of bringing the two halves *n*, *o* into engagement

with each other, whenever the operator treads upon the pedal *t*. The spring *u* throws off the clutch as soon as the foot pressure on the pedal *t* is removed.

5 The end of the shaft *p* is connected by a crank *v* and connecting rod *w* (see particularly Fig. 4) to a lever *x* which is loosely journaled on a pivot *y* attached to the frame *a* of the machine, the pivot extending parallel to the driving shaft *z*. Journaled on the main shaft *z* is the driving belt pulley 2 and fixed on the shaft is a collar 3 in which there is arranged a longitudinal movable coupling pin 4 which is shaped as shown in Fig. 6. This coupling pin has a recess in which there is a spring 5 whose rear end abuts against a fixed transverse abutment 6 and which tends to urge the pin 4 in the direction of the arrow 7.

10 Normally the pin 4 is held in the position shown in Fig. 1 by the knife-shaped end 8 of a double-armed lever 9, 10 which enters the recess in the pin 4 as shown in Figs. 1 and 2. The lever 9, 10 is pivotally mounted on the same stud *y* as the lever *x*. The hubs of the two levers *x* and 9, 10 have the form of ratchet-shaped clutch members which are urged into engagement with each other by a spring 11 on the stud *y*. The 15 ratchet-shaped clutch members on the hubs of the levers are arranged so that when the lever *x* is turned in the direction of the arrow 12 (Fig. 4) the lever 9, 10 is carried round and swung up in the direction of the arrow 12' into the position shown in Fig. 5, in which the knife-shaped end 8 of the arm 9 is out of engagement with the pin 4. A spring 13 whose one end is connected to the frame of the machine tends to keep the lever 9, 10 in the position shown in Fig. 4, i. e., it tends to turn the lever 9, 10 in a counter-clockwise direction.

20

40

The operation of the coupling device will now be described. The initial positions of the mechanism are shown in Figs. 1, 2 and 4. When the mold *e* is moved towards the metal outlet and thus towards the lever *h* after the coupling *n*, *o* has been thrown on by the depression of the pedal *t* the levers *h*, *i*, *k* turn the shaft *p* which then turns the crank *v* and through the connecting rod *w* turns the lever *x* in the direction of the arrow 12. Consequently the lever 9, 10 is turned in the direction of the arrow 12' and a coupling pin 4 is jerked by the spring 5 into a recess 14 in the hub of the continuously rotating pulley 2. The pulley 2 is thus coupled by the pin 4 to the collar 3 and as this collar is fixed on the shaft *z* the latter is turned so as to impart a rotary motion to the cam 15 fixed on the shaft *z*.

45 The coupling pin 4 is returned from the position shown in Fig. 6 to its initial position shown in Figs. 1 and 2 so as to throw off the drive when the driving shaft *z* has

executed one revolution. This restoration of the coupling pin is effected by means of a projection 16 attached to the collar 3, the projection being arranged to engage with an oblique surface of an arm 17 attached to the hub 18 of the lever *z*, when the collar 3 has been turned through a certain angle. The projection 16, in brushing past the arm 17, thus shifts the hub 18 with the lever *z* against the action of the spring 11, which results in the coupling between the two levers *x* and 9, 10 being released. Consequently the spring 13 returns the lever 9, 10 into the position shown in Fig. 4. The knife-shaped end 8 of this lever thus again enters the recess in the pin 4 between the rear end of the same and the abutment 6 (see Fig. 6) and the coupling pin 4 is pulled back into its initial position against the action of the spring 5 so as to release the coupling between the pulley 2 and the driving shaft *z*.

50 The mold *i* is now returned into the initial position shown in Fig. 1 and the casting removed from the same. The mold may then be again advanced to the metal outlet to give rise to another series of operations similar to those already described.

Motion is transferred from the cam 15 to the pressure piston *d* by the connecting rods 19 shown in Figs. 3 and 8 which are connected to a cross beam 20, the latter having a projection 21 that engages with the cam 15. The upper ends of the rods 19 have the shape of pistons 22, arranged in cylinders 23 which latter are attached to rods 25 linked to the upper cross bar 26. The cross bar 26 is attached to the pressure piston or metal ejecting piston *d*. Springs 24 are arranged in the cylinders 23, the lower ends of the springs abutting against the bottoms of the cylinders 23 while the upper ends press against the pistons 22. A spring 27 arranged between the frame of the machine and the cross bar 26 tends to keep the piston *d* in its uppermost position.

55 When the driving shaft *z* and the cam 15 are turned in the direction of the arrow 28 (Fig. 3) the rods 19 with their pistons are pulled downwards and the thrust of the springs 24 against the bottoms of the cylinders 23 transmits the pull of the rods 19 to the rods 25 which, by means of the cross bar 26, press suddenly the piston *d* downwards against the action of the spring 27. The metal is thus ejected from the crucible into the mold *e* until the latter is filled. Further downward motion of the rods 19 will now result in the compression of the springs 24, the piston *d* thus remaining stationary. When the cam 15 has almost executed a complete revolution the downward pull of the rods 19 ceases and the spring 27 pulls the rods with the piston *d* back into their initial positions in which the springs 24 will

again be expanded so that the pistons 22 will be at the upper ends of the cylinders 23. Instead of returning the pressure piston *d* into its initial position by a spring 27, this 5 operation may be performed by a cam 29 arranged beside the cam 15 on the driving shaft 7 and cooperating with a cross beam 30 attached to the rods 19. The cam 29 is shaped so that it does not interfere with the 10 downward motion of the pressure piston but raises the rods 19, and consequently the piston *d*, after the latter has executed its downward stroke. Arranged on one of the rods 25 is a projection 31 which engages 15 with a lever 32 that actuates a valve 33 so as to open the same. The valve 33 controls a pipe or conduit 34 which may be flexible and which connects the mold *e* to a vacuum chamber so that when the valve 33 is opened 20 air is drawn out of the mold *e* in order to obtain perfect castings. Thus, at each downward stroke of the piston *d* air is drawn out of the mold *e*.

I claim:—

- 25 1. Die-casting machine, comprising a crucible with an outlet for molten metal, a mold holder adapted to be moved by hand to said outlet, means for ejecting metal from the crucible through said outlet, a rotary shaft for operating said means, a drive for turning said shaft, motion transferring members for throwing the drive into connection with said shaft, a lever in the path of said mold holder for actuating said members, and means for automatically disconnecting said drive from said shaft when the latter has been turned through a certain angle.
- 40 2. Die-casting machine, comprising a crucible with an outlet for molten metal, a mold holder adapted to be moved by hand to said outlet, means for ejecting metal from the crucible through said outlet, a rotary shaft for operating said means, a drive for turning said shaft, motion transferring members for throwing the drive into connection with said shaft, a lever in the path of said mold holder for actuating said members, a manually operated clutch for coupling said lever to said members, and means for automatically disconnecting said drive from said shaft when the latter has been turned through a certain angle.
- 45 3. Die-casting machine, comprising a crucible with an outlet for molten metal, a mold holder adapted to be moved by hand to said outlet, means for ejecting metal from the crucible through said outlet, a rotary shaft for operating said means, a recessed collar fixed on said shaft, a driving wheel loose on said shaft and having a recess in its hub, a coupling pin slidable in the recess of the collar and positioned so as to be able to enter the recess in said hub, a 50 spring tending to move said pin into said hub, an arm for releasing said pin, motion transferring members for actuating said arm, a lever in the path of said mold holder for actuating said members, and a manually operated clutch for coupling said lever to said motion transferring members.
- 55 4. Die-casting machine, comprising a crucible with an outlet for molten metal, a mold holder adapted to be moved by hand to said outlet, means for ejecting metal from the crucible through said outlet, a rotary shaft for operating said means, a collar fixed on said shaft and having a recess extending parallel to the shaft, a driving wheel loose on said shaft and having a recess in its hub, a coupling pin slidable in the recess of the collar and positioned so as to be able to move into the recess in said hub, a fixed abutment, a spring lodged in the pin and pressing against said abutment 60 and the pin so as to urge the latter towards said hub, a cheek formed in said pin, an arm with a knife edge, a spring urging the arm towards said pin and normally holding it between said cheek and said abutment 65 against the action of the pin actuating spring, a pivot for said arm, a ratchet clutch on said arm, a ratchet sleeve engaging with said ratchet clutch and journalled on said pivot, a second shaft extending parallel to said driving shaft, actuating links for transferring motion from the second shaft to said ratchet sleeve, and a lever in the path of said mold holder for turning said second shaft and thus moving said arm away from said pin, whereby the pin is caused to couple the driving shaft to the driving wheel.
- 70 5. Die-casting machine, comprising a crucible with an outlet for molten metal, a mold holder adapted to be moved by hand to said outlet, means for ejecting metal from the crucible through said outlet, a rotary shaft for operating said means, a collar fixed on said shaft and having a recess extending parallel to the shaft, a driving wheel loose on said shaft and having a recess in its hub, a coupling pin slidable in the recess of the collar and positioned so as to be able to move into the recess in said hub, a fixed abutment, a spring lodged in the pin and pressing against said abutment and the pin 75 so as to urge the latter towards said hub, a cheek formed in said pin, an arm with a knife edge, a spring urging the arm towards said pin and normally holding it between said cheek and said abutment 80 against the action of the pin actuating spring, a pivot for said arm, a ratchet clutch on said arm, a ratchet sleeve engaging with said ratchet clutch and journalled on said pivot, a second shaft extending parallel to said driving shaft, actuating links for transferring motion from the second shaft to said ratchet sleeve, and a lever in the path of said mold holder for turning said second shaft and thus moving said arm away from said pin, whereby the pin is caused to couple the driving shaft to the driving wheel.
- 85 6. Die-casting machine, comprising a crucible with an outlet for molten metal, a mold holder adapted to be moved by hand to said outlet, means for ejecting metal from the crucible through said outlet, a rotary shaft for operating said means, a collar fixed on said shaft and having a recess extending parallel to the shaft, a driving wheel loose on said shaft and having a recess in its hub, a coupling pin slidable in the recess of the collar and positioned so as to be able to move into the recess in said hub, a fixed abutment, a spring lodged in the pin and pressing against said abutment and the pin 90 so as to urge the latter towards said hub, a cheek formed in said pin, an arm with a knife edge, a spring urging the arm towards said pin and normally holding it between said cheek and said abutment 95 against the action of the pin actuating spring, a pivot for said arm, a ratchet clutch on said arm, a ratchet sleeve engaging with said ratchet clutch and journalled on said pivot, a second shaft extending parallel to said driving shaft, actuating links for transferring motion from the second shaft to said ratchet sleeve, and a lever in the path of said mold holder for turning said second shaft and thus moving said arm away from said pin, whereby the pin is caused to couple the driving shaft to the driving wheel.
- 100 7. Die-casting machine, comprising a crucible with an outlet for molten metal, a mold holder adapted to be moved by hand to said outlet, means for ejecting metal from the crucible through said outlet, a rotary shaft for operating said means, a collar fixed on said shaft and having a recess extending parallel to the shaft, a driving wheel loose on said shaft and having a recess in its hub, a coupling pin slidable in the recess of the collar and positioned so as to be able to move into the recess in said hub, a fixed abutment, a spring lodged in the pin and pressing against said abutment and the pin 105 so as to urge the latter towards said hub, a cheek formed in said pin, an arm with a knife edge, a spring urging the arm towards said pin and normally holding it between said cheek and said abutment 110 against the action of the pin actuating spring, a pivot for said arm, a ratchet clutch on said arm, a ratchet sleeve engaging with said ratchet clutch and journalled on said pivot, a second shaft extending parallel to said driving shaft, actuating links for transferring motion from the second shaft to said ratchet sleeve, and a lever in the path of said mold holder for turning said second shaft and thus moving said arm away from said pin, whereby the pin is caused to couple the driving shaft to the driving wheel.
- 115 8. Die-casting machine, comprising a crucible with an outlet for molten metal, a mold holder adapted to be moved by hand to said outlet, means for ejecting metal from the crucible through said outlet, a rotary shaft for operating said means, a collar fixed on said shaft and having a recess extending parallel to the shaft, a driving wheel loose on said shaft and having a recess in its hub, a coupling pin slidable in the recess of the collar and positioned so as to be able to move into the recess in said hub, a fixed abutment, a spring lodged in the pin and pressing against said abutment and the pin 120 so as to urge the latter towards said hub, a cheek formed in said pin, an arm with a knife edge, a spring urging the arm towards said pin and normally holding it between said cheek and said abutment 125 against the action of the pin actuating spring, a pivot for said arm, a ratchet clutch on said arm, a ratchet sleeve engaging with said ratchet clutch and journalled on said pivot, a second shaft extending parallel to said driving shaft, actuating links for transferring motion from the second shaft to said ratchet sleeve, and a lever in the path of said mold holder for turning said second shaft and thus 130 moving said arm away from said pin, whereby the pin is caused to couple the driving shaft to the driving wheel.

moving said arm away from said pin, whereby the pin is caused to couple the driving shaft to the driving wheel, a projection that rotates with said collar, a cam on said ratchet sleeve in path of said projection for moving the ratchet sleeve out of engagement with ratchet clutch whereby the knife edge of said arm is permitted to be forced by its said spring between said abutment and cheek to 10 remove the coupling pin from the recess in the hub of the driving wheel.

6. Die-casting machine comprising a crucible with an outlet for molten metal, a mold holder adapted to be moved by hand to said 15 outlet, a piston for ejecting the metal through said outlet, a driving shaft, a collar fixed on said shaft and having a recess extending parallel to the shaft, a driving wheel loose on said shaft and having a recess 20 in its hub, a coupling pin slidable in the recess of the collar and positioned so as to be able to move into the recess in said hub, a fixed abutment, a spring lodged in the pin and pressing against said abutment and the 25 pin so as to urge the latter towards said hub, a cheek formed in said pin, an arm with a knife edge, a spring urging the arm towards said pin and normally holding it between said cheek and said abutment 30 against the action of the pin actuating spring, a pivot for said arm, a ratchet clutch on said arm, a ratchet sleeve engaging with said ratchet clutch and journalled on said pivot, a second shaft extending parallel to said driving shaft, actuating links for transferring motion from the second shaft to said ratchet sleeve, a lever in the path of said mold holder for turning said second shaft and thus moving said arm away from said 35 pin, whereby a pin is caused to couple the driving shaft to the driving wheel, a cam on the driving shaft for operating said piston, and means for restoring the piston to its non-operative position.

45 7. Die-casting machine comprising a crucible with an outlet for molten metal, a mold holder adapted to be moved by hand to said outlet, a piston for ejecting the metal through said outlet, a driving shaft, a collar fixed on said shaft and having a recess extending parallel to the shaft, a driving wheel loose on said shaft and having a recess in its hub, a coupling pin slidable in the recess of the collar and positioned so as 50 to be able to move into the recess in said hub, a fixed abutment, a spring lodged in the pin and pressing against said abutment and the pin so as to urge the latter towards said hub, a cheek formed in said pin, an arm with a knife edge, a spring urging the arm towards said pin and normally holding it between said cheek and said abutment against the action of the pin actuating spring, a pivot for 55 said arm, a ratchet clutch on said arm, a ratchet sleeve engaging with said ratchet

clutch and journalled on said pivot, a second shaft extending parallel to said driving shaft, actuating links for transferring motion from the second shaft to said ratchet sleeve, a lever in the path of said mold holder for turning said second shaft and thus moving said arm away from said pin, whereby a pin is caused to couple the driving shaft to the driving wheel, a cam on the driving shaft for operating said piston, and a second cam on the driving shaft for restoring the piston to its non-operative position.

8. Die-casting machine comprising a crucible with an outlet for molten metal, a mold holder adapted to be moved by hand to said outlet, a piston for ejecting the metal through said outlet, a driving shaft, a collar fixed on said shaft and having a recess extending parallel to the shaft, a driving wheel loose on said shaft and having a recess in its hub, a coupling pin slidable in the recess of the collar and positioned so as to be able to move into the recess in said hub, a fixed abutment, a spring lodged in the pin and pressing against said abutment and the pin so as to urge the latter towards said hub, a cheek formed in said pin, an arm with a knife edge, a spring urging the arm towards said pin and normally holding it between said cheek and said abutment against the action of the pin actuating spring, a pivot for said arm, a ratchet clutch on said arm, a ratchet sleeve engaging with said ratchet clutch and journalled on said pivot, a second shaft extending parallel to said driving shaft, actuating links for transferring motion from the second shaft to said ratchet sleeve, a lever in the path of said mold holder for turning said second shaft and thus moving said arm away from said pin, whereby the pin is caused to couple the driving shaft to the driving wheel, an extensible spring connecting member connected to said piston, and a cam on said driving shaft for operating said piston through said extensible member.

9. Die-casting machine comprising a crucible with an outlet for molten metal, a mold holder adapted to be moved by hand to said outlet, a piston for ejecting the metal through said outlet, a driving shaft, a collar fixed on said shaft and having a recess extending parallel to the shaft, a driving wheel loose on said shaft and having a recess in its hub, a coupling pin slidable in the recess of the collar and positioned so as to be able to move into the recess in said hub, a fixed abutment, a spring lodged in the pin and pressing against said abutment and the pin so as to urge the latter towards said hub, a cheek formed in said pin, an arm with a knife edge, a spring urging the arm towards said pin and normally holding it between said cheek and said abutment against the action of the pin actuating spring, a pivot for 115 said arm, a ratchet clutch on said arm, a ratchet sleeve engaging with said ratchet

5 said arm, a ratchet clutch on said arm, a ratchet sleeve engaging with said ratchet clutch and journalled on said pivot, a second shaft extending parallel to said driving shaft, actuating links for transferring motion from the second shaft to said ratchet sleeve, a lever in the path of said mold holder for turning said second shaft and thus moving said arm away from said pin, 10 whereby the pin is caused to couple the driving shaft to the driving wheel, a cross bar attached to said piston, connecting rods linked to said cross bar, a cross beam, a cam on said driving shaft for reciprocating said cross beam, links connected to said cross beam, 15 shoulders at the ends of said links, members attached to said connecting rods which embrace said links at a distance from said shoulders, and springs between said 20 members and said shoulders.
